DESIGN FOR A CURTAIN, DRAPERY, &c.

UNITED STATES PATENT OFFICE.

CANDACE WHEELER, OF NEW YORK, N. Y.

DESIGN FOR A CURTAIN, DRAPERY, &c.

SPECIFICATION forming part of Design No. 19,074, dated April 30, 1889.

Application filed February 20, 1889. Serial No. 300,628. Term of patent 7 years.

To all whom it may concern:

Be it known that I, CANDACE WHEELER, a citizen of the United States, residing at New York, in the county of New York and State 5 of New York, have invented and produced a certain new and original Design for Curtains, Draperies, and like Fabrics; and I do hereby declare the following to be a full, clear, and exact description of the invention, 10 such as will enable others skilled in the art to which it appertains to make and use the same.

My new and original design represented in the accompanying drawing is intended for 15 the ornamentation of fabrics for curtains, draperies, hangings, &c.

It consists in the representation in outline of the flowers, leaves, and stems of the chrysanthemum confused over the entire surface 20 of the fabric.

In the accompanying drawing, A is the fabric, of any desired color or shade, which constitutes the groundwork for the design. B are the stems, C the leaves, and D the flowers of the chrysanthemum, all being 25 mingled and confused over the entire surface of the fabric, which may be of any size.

I claim—

The design herein described and shown for the ornamentation of fabrics for curtains, 30 draperies, &c., the same consisting of the representation in outline of the flowers, stems, and leaves of chrysanthemum plants confused upon the surface of the fabric, substantially as herein set forth. 35

In testimony whereof I have affixed my signature in presence of two witnesses.

CANDACE WHEELER.
